UNITED STATES PATENT OFFICE.

GEORGE CUGLEY, OF SPRINGFIELD, OHIO, ASSIGNOR TO THE BUCKEYE INCUBATOR COMPANY, OF SPRINGFIELD, OHIO, A CORPORATION OF OHIO.

HOVER.

1,227,120.

Specification of Letters Patent. Patented May 22, 1917.

Application filed April 10, 1916. Serial No. 90,249.

To all whom it may concern:

Be it known that I, GEORGE CUGLEY, a citizen of the United States, residing at Springfield, in the county of Clark and 5 State of Ohio, have invented certain new and useful Improvements in Hovers, of which the following is a specification.

This invention relates to improvements in hovers for chicks, it more particularly 10 relating to a hover of the central heater type.

One of the objects of the invention is to provide for furnishing the heater with an abundant supply of fresh air to not only 15 furnish a better combustion but also to eliminate the danger of explosions.

A further object of the invention is to improve the construction and make more effective the operation of devices of this 20 character.

In the accompanying drawings:—

Figure 1 is a vertical section on the line 1—1 of Fig. 2.

Fig. 2 is a bottom plan view.

25 The hover consists essentially of a heat chamber and a heater centrally located therein. The heat chamber is cylindrical in shape and has a top and side of double thickness, 1 and 4 representing the top members and 2 and 2' the side members; insulating material 5, preferably asbestos, being placed between the respective members. The top 1 is formed flat in a horizontal direction and the side 2 straight in a vertical 30 direction, but the bottom portion or radiator 3, the outer edge of which is secured to the lower edge of the side 2, projects inwardly so as to form a bottom or radiator of a cone shape. The top 1 and wall 4 are 35 formed with a central opening 6 and the bottom or radiator 3 is formed with a central opening 7 coinciding with the opening 6. A cover 8 closes the opening 6 and supported from this cover by straps 9 and a 40 lower cross piece 10 is the heater. The heater is an oil burning lamp, 11 representing the front, 12, the chimney or flue and 13 the burner. The flue 12 projects to a point 45 a short distance above the opening 7 formed in the bottom 3 so that the products of combustion will circulate through the open 50 space between the edges of the openings 6 and 7 and into the interior of the heat chamber and thence out through the flues 14 which are supported from the top 1 and

extend down to a point in close proximity to the bottom 3 in the usual way.

The device thus formed is supported upon legs 15 connected preferably to the bottom 3 so as to support the hover above the 60 ground line and the hovering space beneath the heat chamber is inclosed by the usual curtain 16. I also preferably surround the heater by a shield 17 of wire mesh, the upper edges of which are provided with a 65 series of flexible metallic strips 18 which are bent over the inner edge of the bottom 3 to support the shield; this shield being solely for the purpose of preventing the chicks from coming in too close contact with the lamp. A tube 19 is extended through the walls 1, 4 and 3 to permit the insertion of a thermometer in the hovering space.

70 By this construction it will be seen that the heater is so arranged that it receives a free circulation of air completely about the same from all directions in the hovering chamber, the open mesh screen in nowise interfering with this result, the air entering between the curtains 16, which extend completely around the hovering chamber and then passing through the hovering chamber, up around all sides of the flue of the heater as well as through the same and then 75 entering the heat chamber, and leaving through the flues 14. This arrangement also insures a supply of fresh air at all times in the hovering chamber.

80 By forming the bottom of the heat chamber in the shape of a frustum of a cone, it will be seen that the lowest point of the radiating surface of the heat chamber; or that point closest to the chicks, is at the outer part thereof so that the warmest place 85 in the hovering space will be at a point close to the curtains, which is desirable to prevent the chicks from crowding toward the center, which they will do if they find that to be the warmest spot of the hovering space. 90 By arranging the flues 14 at a point close to the side walls 2, in connection with the peculiar form of the radiator, it will be seen that the lower ends of the flues can be located at the lowest point of the heat chamber, which is essential to insure the proper 95 heating of the radiating surface.

100 Having thus described my invention, I claim:—

1. In a device of the character described, 110 a circular heat chamber having a flat top,

a vertical outer side wall and a bottom which is inclined upwardly from the lower edge of said side wall toward the top, legs secured to the outer edge of said inclined bottom 5 to support said heat chamber above the ground line to form a hovering chamber beneath the same, a curtain suspended from the outer lower edge of said chamber to inclose said hovering space, said heat chamber 10 having aligned circularly arranged openings through its top and bottom, a cover for the top opening and a heater including a flue suspended from said cover and located in said hovering space with all portions there- 15 of exposed to the air in said hovering space, said flue being spaced away from the edges of the opening through the bottom of said heat chamber so as to permit a circulation of air about all portions of the same, said 20 heat chamber being provided with a continuous passageway leading to the interior of the same between the edges of the top and bottom openings, and a flue suspended from the top of said heat chamber and ex- 25 tending to a point in proximity to the bottom thereof near the side wall of said chamber.

2. In a device of the character described, a circular heat chamber supported above the 30 ground line to form a hovering chamber

beneath the same, a curtain suspended from the heat chamber so as to inclose said hovering chamber, said heat chamber having a flat top, a side wall and a bottom which is inclined upwardly from the lower end of 35 said side wall toward the top, said heat chamber having aligned circularly arranged openings through its top and bottom, a cover for the top opening and a heater including a flue suspended from said cover 40 and located in said hovering space with all portions thereof exposed to the air in said hovering space, said flue being spaced away from the edges of the opening through the bottom of said heat chamber so as to permit a circulation of air about all portions 45 of the same, said heat chamber being provided with a continuous passageway leading to the interior of the same between the edges of the top and bottom openings, and a flue suspended from the top of said heat chamber and extending to a point in proximity to the bottom thereof near the side wall of said chamber.

In testimony whereof, I have hereunto set 55 my hand this 4th day of April 1916.

GEORGE CUGLEY.
